UNITED STATES PATENT OFFICE

133,302

DESIGN FOR A COMBINED DESK SET AND ENVELOPE OPENER

Richard W. Harrison, Charlestown, Mass.

Application May 25, 1942, Serial No. 107,004

Term of patent 7 years

To all whom it may concern:

Be it known that I, Richard W. Harrison, a citizen of the United States and residing at 106 Washington Street, Charlestown, in the county of Suffolk and State of Massachusetts, have invented a new, original, and ornamental Design for a Combined Desk Set and Envelope Opener, of which the following is a specification, reference being had to the accompanying drawings, forming a part thereof.

Figure 1 is a perspective view of a combined

desk set and envelope opener, showing my new design;

Figure 2 is a top plan view thereof;

I claim:

The ornamental design for a combined desk set and envelope opener, substantially as shown.

RICHARD W. HARRISON.
